SPRING HEAD RAIL SPIKE

George W. Muller, Miami, Fla.

Application July 23, 1940, Serial No. 347,052

22 Claims. (Cl. 238—366)

This invention relates to railway spikes.

More specifically, the invention relates to spikes for retaining railway rails against lateral movement as well as against creeping while permitting wave motion therein as induced by rolling stock traveling over the railway, the spikes also retaining the tie plates in position on the ties whereby the entire track assemblage is maintained in proper operating condition.

The improved spikes in accordance with this invention are constructed of bar spring steel, and are adapted for operative association with railway ties, tie plates, and rails in such manner as to offer yieldable resistance to vertical movement of the rails as well as longitudinal or creeping movement thereof.

It is fully appreciated that yieldable rail retaining spikes of various forms have heretofore been proposed or used, and while such prior constructions may have in some instances proved satisfactory in their ability to retain the rails against creeping, they nevertheless were open to objection that they failed to permanently retain their rail retaining abilities and in many instances the tie plates gradually became loose on the ties with the result that the rails were free to shift laterally to some extent.

This objection to prior proposed spike constructions was due to the fact that the spikes either included yieldable rail engaging members held in position by rigid spikes driven through the tie plates and into the ties, or they included unitary members comprising yieldable rail flange engaging portions and straight shank portions for insertion through the tie plates and into the ties.

In either of these forms of construction, the tie engaging portions were retained in position solely by their frictional engagement within the ties and during the repeated vibrations or wave motions in the rails the tie engaging portions gradually worked upwardly out of purchase in the ties which not only impaired the efficiency of the yieldable rail engaging portions but also resulted in the tie plates becoming loose with consequent lateral shifting of the rails.

It is accordingly a primary object of this invention to provide yieldable railway spikes which in use retain all the cooperating track elements in correct position and thereby overcome the above noted objections to prior spike constructions.

A further object of the invention is the provision of unitary spikes constructed from bar spring steel and including tie engaging shanks

and rail engaging heads, the shanks being so formed and the heads related thereto in such manner that the shanks frictionally engage opposed walls in the tie plate apertures and the heads engage the rail flanges under yieldable reaction and augment the engagement between the shanks and the walls of the tie plate apertures during flexing thereof as occasioned by vibration in the rails.

A still further object of the invention is the provision of yieldable railway spikes having rail flange engaging heads which include spring steel bar portions variously bent in planes substantially at right angles to each other whereby such bar portions are subjected to both compression and twisting in the flexing thereof as occasioned by rail vibrations with the result that such heads offer substantial yieldable resistance to displacement of the rails.

A still further object of the invention is the provision of yieldable railway spikes of the above noted character which are simple in construction, durable, efficient and dependable in use, and which are capable of manufacture and installation at relative low cost.

For a more complete understanding of the nature and objects of the invention, reference will be had to the following detailed description, taken in connection with the accompanying drawings, wherein:

Figure 1 is a transverse section of portions of a tie, tie plate, and rail showing a spike constructed in accordance with one embodiment of the invention in elevation and in operative connection with the tie, tie plate, and rail.

Figure 2 is a fragmentary longitudinal section of the tie plate showing the rail flange and spike in elevation.

Figure 3 is a top plan view of the structure illustrated in Figure 1.

Figure 4 is a view similar to Figure 1 showing a spike in accordance with a further embodiment of the invention.

Figure 5 is a view similar to Figure 2 showing the spike of Figure 4 at right angles thereto.

Figure 6 is a view similar to Figure 1 showing a spike in accordance with a further embodiment of the invention.

Figure 7 is a top plan view of the structure shown in Figure 6.

Figure 8 is a view similar to Figure 1 showing a spike in accordance with a further embodiment of the invention.

Figure 9 is a top plan view of the structure illustrated in Figure 8.

Figure 10 is a view similar to Figure 2 showing the spike of Figure 8 at right angles thereto.

Figure 11 is a view similar to Figure 1 showing a spike according to a still further embodiment of the invention.

Figure 12 is a view similar to Figure 2 showing the spike of Figure 11 at right angles thereto.

Figure 13 is a top plan view of the structure illustrated in Figure 11.

Figure 14 is a view similar to Figure 2 showing a spike in accordance with another embodiment of the invention.

Figure 15 is a view similar to Figure 1 showing the spike of Figure 14 at right angles thereto.

Figure 16 is a fragmentary perspective view showing the head of a spike of a still further form in operative association with a rail flange.

Figures 17 and 18 are views similar to Figure 1 showing a spike in accordance with a still further embodiment of the invention, Figure 17 showing the spike being applied and Figure 18 showing the spike in applied position.

Referring now in detail to the drawings by the use of reference characters, and referring first to the embodiment of the invention illustrated in Figures 1, 2 and 3, S designates a spike in operative association with a rail R, tie plate P and tie T.

The spike is preferably constructed from a single piece of square bar steel and includes a shank 10 merging into a neck 11 at an off-set 12 and the neck merges into a head formed by bending the bar downwardly and laterally toward the rail as indicated at 13 and then bending the bar toward the left longitudinally of the rail as at 14. The bar is further bent downwardly at 15 providing a terminal rail engaging arm 16 which in top plan is parallel with the rail flange edge and which in elevation extends downwardly and toward the neck 11, terminating directly behind the neck and having its lower corner 17 bearing on the rail flange.

The offset 12 provides for clearance of the edge of the rail flange by the neck 11 and also provides a shoulder 18 which frictionally engages the inner wall of the tie plate spike receiving aperture a when the shank 10 is driven into the tie and the neck 11 yieldably engages the upper edge of the outer wall of the aperture at 19 which forms the fulcrum point for the flexing neck and head and due to the yieldable reaction on the walls of the tie plate aperture at points 18 and 19 the shank is retained against withdrawal from the tie T as would otherwise occur in the course of repeated track vibrations caused by rolling stock moving over the rails.

By the provision of the bends 13, 14 and 15 together with the outwardly inclined and slightly bowed neck 11 and the downwardly inclined rail flange engaging arm 16 sufficient length of bar material is available to give great flexibility to the head and arm which at the same time the relatively heavy bar steel offers sufficient resistance to flexing to hold the rail against lateral and creeping movement.

This improved spike is highly simple in construction, easy to assemble with standard tie plates and when in operative position, yieldably retains the rail as well as the tie plate in position while permitting the customary wave motion in the rail.

The spike S' in accordance with the embodiment of Figures 4 and 5 is preferably formed from a single piece of bar steel also, the piece being bent substantially centrally of the length 75

thereof and the two portions laid in contact whereby providing a shank, neck and head of two plies whose joint cross section is substantially square as in the form of Figures 1, 2 and 3.

5 The shank 21 is pointed at its lower end and adjacent its upper end is offset at 22 wherefrom it merges into a neck 23 which through the offset 22 is displaced outwardly to clear the flange of the rail R.

10 The neck 23 merges into a head formed by bending the neck laterally toward the rail flange as at 24, then to the left in parallelism with the rail as at 25, then bending the inner or lower layer or lamina as at 26 providing a rail flange engaging arm 27 extending longitudinally of the rail and inclining downwardly from the bend 26 toward the neck 23 and terminating at a point back of the neck whereat a terminal corner 28 at the arm yieldably engages the rail flange.

15 The upper or outer layer or lamina is bent downwardly at 29 and terminates in a vertical rail flange engaging arm 30 which is co-planar with the arm 27 and engages the rail flange through its end surface in longitudinally spaced relation to the first arm engaging point 28.

20 This form of spike also has a shoulder 31 yieldably and frictionally engaged with the inner wall of the tie plate aperture a and a fulcrum bearing engagement 32 with the upper edge of the outer wall of the aperture.

25 Thus this form of spike will function similarly to that of Figures 1, 2 and 3 but will have a two point rail flange engagement whereby it will more effectively hold the rail against creeping. The double layer construction will also provide for greater flexibility in the neck, head, and arm.

30 In the embodiment of Figures 6 and 7 the spike S² includes a shank 34 which is bent intermediate its ends providing a tie plate aperture wall engaging portion 35, a knee portion 36 for engagement beneath the lower inner corner of the tie plate aperture, a leg 37 inclined outwardly and terminating in an incurved foot 38.

35 The head is provided by a bend 39 to one side 45 of the shank and terminating in an under-slung arm 40 for extending generally longitudinally of the rail and for engaging the rail flange at its lower terminal corner.

40 The spike is driven into a tie and the knee 36 and foot 38 hold the shank in driven position.

45 A wedge spike 41 having a right angular head 42 and a chisel-point lower end 43 is preferably provided for additional securing means for the spike S². This wedge spike is driven through the tie plate aperture a in contact with the outer wall thereof, the head 42 serving as hammer impact means and engaging over the head of spike S² to drive same into position and retain it there. The lower chisel end of the wedge spike will urge the shank thereof into contact with the foot 38 and thereby urge same into better binding contact with the tie.

50 This form of spike will function similarly to that of Figures 1, 2 and 3 in holding the rail in position.

55 The spike S³ in accordance with the embodiment of Figures 8, 9 and 10 includes a shank 45 which is bent sidewise or off-set at 46 at the position of the tie plate aperture a when the shank is driven into position in the tie, this offset provides engagement of the shank with the inner and outer corners of the inner and outer walls respectively at the aperture a as indicated at 47 and 48.

60 These points of engagement hold the shank

in position and the contact point 48 provides a fulcrum about which the yieldable head oscillates.

This offset 46 is provided by deflecting the neck 49 outwardly as respects the rail flange in order to clear such flange and with this construction, the side of the shank adjacent the rail is forced toward the rail upon driving the spike into position, resulting in the yieldable contact at the point 47.

By the spacing of the neck 49 from the edge of the rail flange the flexing of the neck is unobstructed as is also the wave motion in the rail.

The head of the spike is provided by bending the upper end of the neck 49 slightly downwardly and to the right at 50 as considered when the spike is in rail holding position.

By bending down slightly, a hammer driving point is provided at 51, the head of the spike further includes the bend 52 which terminates in an arm 53 extending downwardly longitudinally at the rail and having the lower corner 54 of its free end bearing on the rail flange.

In this particular construction, upward movement of the rail against the end of the arm 53 and on through the head and neck 49, will cause all to have a slight oscillating or twist movement, similar to a coil spring whereby the rail will be effectively held against lateral movement and creeping and the offset 46 together with the yieldable resistance of the neck, head, and arm will positively maintain the shank 45 in the engaging position.

The spike S⁴ according to the embodiment of Figures 11, 12 and 13 includes the shank 56 and 35 a neck 57 joining the shank at the offset which provides the shoulder 58 and fulcrum 59 respectively engaged with the inner and outer walls of the tie plate aperture.

The neck extends at a slight angle to the shank 40 longitudinally of the rail considering the spike in position, as is clearly indicated in Figure 12, the neck is then bent in opposition to the inclination of the neck as at 60 and thence extending slightly downwardly to provide a driving head at the bend 60.

From the bend 60 the head is continuously curved in coil formation in top plan as is clearly indicated in Figure 13, the material of the coil continuously extending downwardly as indicated in Figure 12 and terminating in a downwardly inclined arm 61 having the lower corner 62 of its free end engaged with the rail flange.

As will be seen from Figures 12 and 13, the coil includes oppositely facing semi-circular bends 63 and 64 with the former considerably larger than the latter, and with the arm 61 extending diametrically at the bend 63 adjacent the edge of the rail flange and terminating behind the neck 57 and extending in parallelism with the portion 65 interconnecting the bends 63 and 64.

This construction provides a highly efficient rail retaining means in that upon upward movement of the rail, the various curved portions embodied in the head are not only subjected to vertical flexing but the entire head undergoes a torsional twist whereby substantial yieldable resistance is offered to displacement of the rail.

The spike S⁵ in accordance with the embodiment of Figures 14 and 15 is similar to that of Figures 4 and 5 in that it is of dual ply construction and presents a two point rail flange engagement.

The spike, similar to that of Figures 4 and 5 73

is preferably constructed from a single length of bar steel of rectangular cross section.

The bar is bent intermediate its ends with the two parts placed in contact to provide a shank 67 which adjacent its upper end is offset at 68 whence it merges into the neck 69 which as indicated in Figure 15 is outwardly offset from the edge of the rail flange.

The upper end of the neck is bent at 70 in a direction longitudinally of the rail and the two bar portions continue in contact a short distance from this bend whereupon the inner or lower bar portion is extended and bent downwardly providing an arm 71 whose lower terminal corner 72 is adapted to engage the rail flange.

The outer or upper bar portion, is bent at 73 in a direction transverse to the rail and terminates in a downwardly inclined arm 74 whose lower terminal corner 75 is adapted to engage the rail flange. The rail flange engaging points 72 and 75 are substantially spaced longitudinally of the rail, with one on each side of the neck 69.

The spike S⁶ in accordance with the embodiment of Figure 16 includes a shank 77 comprising four contacting steel bar portions of rectangular cross section, the bar portions including pairs 78 and 79.

Each pair of bar portions 78, 79 may be constructed from a single length of bar steel bent intermediate its ends as in the embodiment of Figures 4, 5, 14 and 15 and the lower ends of the two bent over bars may be suitably secured and pointed for driving into a tie.

Each pair of bar portions 78, 79 is bent at 80 in opposition providing oppositely extending downwardly inclined laminated arms 81.

The free ends of the lower bar portions in the arms 81 are adapted to contact the rail flange and the upper bar portions in the arms act as reinforcements whereby substantial yieldable resistance is offered to displacement of the rail.

The spikes S⁷ in accordance with the embodiment of Figures 17 and 18 is similar to that of Figures 6 and 7. The flexible spike includes a shank similar to that in Figures 6 and 7, having a knee 83, leg 84, and foot 85. A wedge spike 86 is preferably used to more positively hold the spike S⁷ in position and when driven into the tie holds the spike substantially as in the embodiment of Figures 6 and 7 except that the shank is held in engagement with the rail flange instead of being spaced therefrom as in Figures 6 and 7.

The head of spike S⁷ is however quite different from that in Figures 6 and 7 in that it includes reverse bends 86' and 87, the latter of which terminates in an arm 88 whose free end is adapted to be engaged by an overhanging head 89 on the wedge spike 86.

The bend 87 is adapted to engage the rail flange and the spike head included by the bends 86 and 87 and the arm 88 is substantially compressed by the wedge spike head 89 with the bend 87 engaging the rail flange substantially inwardly of the edge thereof.

The wedge spike 86 is preferably provided with a shoulder 90 for engagement with the tie plate P for limiting the distance to which the wedge spike can be driven into the tie and consequently the compression imparted to the head of the spike S⁷.

While the various spikes disclosed are intended to be constructed in quantities for application to trackways, they are for the most part herein described in relation to the rails merely as a con-

venience in describing the various directions of extension of the spike neck and head parts.

It should be readily appreciated from the foregoing disclosure that in accordance with this invention, railway spikes are provided which substantially fulfill the maximum requirements of such devices in that they act to maintain the rails in position on the tie plates under substantial yielding reaction to wave motion and they also function to retain a frictional grip with the tie plates and which grip is augmented during vibration or wave motion of the rails.

With this characteristic, the spikes once assembled with the tie plates and rails will permanently retain their rail retaining properties and will also retain the tie plates in firm engagement with the ties whereby the rails will be positively maintained against lateral displacement.

It is to be particularly noted that the heads of the spikes embody relatively great lengths of bar steel whereby fatigue will be reduced to a minimum during the successive flexing thereof as occasioned by wave motion in the rails and the various angularly disposed bends in the heads impart maximum flexibility thereto with provision for substantial resistance to movement of the rails.

In most of the embodiments disclosed the spike heads terminate in arms which yieldably engage the rail flanges of an end corners thereof whereby providing a frictional grip longitudinally of the flanges.

Furthermore, in many of the embodiments disclosed the yieldable spike heads present two rail flange engaging points longitudinally of the rails which material reduce the possibilities of rail creeping and since the shanks and necks of the spikes meet at offset portions defining tie plate aperture wall engaging shoulders as well as fulcrum engagements with the aperture walls the spike shanks will have a substantial frictional grip with such walls and this grip will be augmented during movement of the heads which otherwise would have a tendency to urge the shanks upwardly out of purchase in the ties.

While but certain specific embodiments of the invention have been disclosed, such are to be considered as illustrative only, and not restrictive, the scope of the invention being defined in the subjoined claims.

What is claimed and desired to be secured by United States Letters Patent is:

1. In combination with an apertured tie plate and a rail supported thereon; an integral rail retaining spike comprising a shank extended through said aperture and into a tie, a yieldable arm having a free end portion extending longitudinally of the rail and downwardly into engagement with a flange of said rail, and a connection between said shank and said arm comprising a portion reversely curved in a substantially horizontal plane and providing torsional resistance to the yielding of said arm, said connection overlying the rail flange.

2. A track spike formed of rectangular bar steel and comprising a shank having a driving top end, and a yieldable head in continuation of said shank and comprising a curved portion at one side of the shank and in a plane at right angles to the axis thereof, and a rail flange engaging portion in continuation of said curved portion and paralleled with an adjacent side of said shank.

3. A track spike according to claim 2 wherein the plane of said curved portion is below the top of the shank.

4. A track spike according to claim 2 wherein said curved portion is substantially semi-circular and wherein said rail flange engaging portion is at an angle to the plane of said curved portion.

5. A track spike comprising a single piece of bar spring steel and including a substantially straight shank having a rounded driving head, the shank being extended from the head in the form of a semi-circular bend in a plane at right angles to the axis of the shank and terminating in a straight rail flange engaging arm in downwardly inclined relation to said plane.

15 6. A track spike comprising a substantially straight shank bent at its upper end and continued in a substantially straight portion downwardly inclined relative to the axis of the shank, a relatively straight rail flange engaging portion extending in opposition to said first straight portion and downwardly inclined relatively to the axis of said shank, and a curved portion in a plane at right angles to the axis of the shank and interconnecting said relatively straight portions.

20 7. A track spike according to claim 6 wherein said relatively straight portions are in spaced parallel planes.

8. A track spike according to claim 6 wherein the upper end of said shank projects above said straight and curved portions for providing an unobstructed driving head.

30 9. In combination with an apertured tie plate and a rail supported thereon; a retaining spike comprising a shank inserted through said aperture and into a tie, a yieldable head unitary with said shank and comprising an arm extending longitudinally of the rail and having corner contact engagement with the rail flange at its free end, and a substantially semi-circular curved portion interconnecting said arm and said shank and being substantially in a horizontal plane.

40 10. A unitary railway spike comprising a shank, and a yieldable head including a portion of coil formation in a plane perpendicular to the shank and below the top thereof, and a rail flange engaging arm at an angle to said plane, said coil portion interconnecting said shank and said arm.

45 11. A railway spike comprising a substantially straight shank continued at its top in the formation of a yieldable head, the head including opposed curved portions in a plane normal to said shank and a rail flange engaging portion downwardly inclined relatively to said plane, said opposed curved portions interconnecting said shank and said flange engaging portion.

50 12. A railway spike comprising a substantially straight shank and a yieldable head unitary therewith, the head including opposed semi-circular portions at opposite sides of the axis of said shank, one of said portions terminating in a rail flange engaging arm, and the other of said portions interconnecting said one portion and said shank.

55 13. In combination with a tie supported apertured tie plate and a rail supported thereon; a retaining spike comprising a relatively straight shank extended through said aperture and into the tie, and a yieldable head unitary with, and in continuation of the shank, the head including a semi-circular portion in a plane normal to said shank and overlying a flange of said rail, and the semi-circular portion terminating in a rail flange engaging arm extending longitudinally of the rail.

60 14. The structure according to claim 13 wherein said flange engaging arm is radially disposed

with respect to the axis of said semi-circular portion.

15. A track spike comprising a substantially straight shank and a yieldable head unitary with the shank, the head including a pair of semi-circular portions in a plane normal to said shank, one of said semi-circular portions terminating in a rail flange engaging arm extending radially of the axis of said other semi-circular portion, and the other of said portions interconnecting said one portion and said shank.

16. A track spike comprising a substantially straight shank and a yieldable head unitary therewith, said head including a semi-circular portion of relatively large radius at one side of the axis of said shank and a reversed semi-circular portion of relatively small radius at the opposite side of the axis of said shank, the last portion terminating in a rail flange engaging arm radially disposed with respect to the axis of the first portion, said first portion interconnecting said last portion and said shank.

17. The structure according to claim 16 where-
in said portions are in a plane normal to the axis
of said shank and said arm extends downwardly
relative to said plane.

18. A track spike comprising a shank of rectangular cross-section and a yieldable head comprising a pair of rail flange engaging portions extending from the same side of said shank and terminating at opposite sides of the plane of said side.

19. A track spike comprising a substantially straight shank and a yieldable head unitary therewith, said head including a pair of arms extending in parallelism from one side of the shank, one of said arms being downwardly extended at the same side of the shank and the other arm

extending downwardly in a reverse direction and terminating at the opposite side of said shank.

20. A track spike comprising a substantially straight shank and a yieldable head unitary therewith said head including a downwardly inclined rail flange engaging portion at one side of the shank, a second rail flange engaging portion overlying and parallel with the first portion for a part of the extent thereof, the second portion being deflected from the first portion in the form of a bend at right angles to the shank and thence extending downwardly in opposition to the first portion for engagement with a rail flange at the opposite side of the shank.

15 21. A track spike comprising a substantially straight shank and a yieldable head unitary therewith, the head including oppositely extending downwardly deflected rail flange engaging portions and a semi-circular portion in one of said first portions and cooperating with both of the first portions in resisting deflection thereof under torsional strain.

25 22. A track spike formed from a single bar of steel bent intermediate its ends from which point the two portions are in side by side contact providing a substantially straight shank, the portions of the head of the shank being bent substantially at right angles to the shank and extending substantially straight in superposed relation for a distance from one side of the shank, the lower portion being downwardly extended from the remote point of superposition to provide a rail flange engaging arm, the top portion being bent in a plane at right angles to the shank and extended therefrom in the form of a downwardly extended arm substantially in direct opposition to the first arm to engage a rail flange at a point remote from that of the first arm.

30 35 GEORGE W. MULLER.
